John O. Burman.

ATTORNEY

UNITED STATES PATENT OFFICE.

JOHN O. BURMAN, OF LOWELL, MASSACHUSETTS.

BURNER.

1,259,832.

Specification of Letters Patent. Patented Mar. 19, 1918.

Application filed January 3, 1916. Serial No. 70,016.

To all whom it may concern:

Be it known that I, JOHN O. BURMAN, a citizen of the United States, residing at Lowell, in the county of Middlesex and 5 State of Massachusetts, have invented certain new and useful Improvements in Burners, of which the following is a specification.

My present invention has relation to certain new and useful improvements in gas 10 burners and as its primary object it contemplates the provision of a novel device of this character that is especially designed to be used in connection with conventional forms of grates and bed plates therefor in 15 order to expedite the starting or the reviving of the fire.

Another object of my invention is to provide a burner of this nature that may be cast in a single piece and afterward cored 20 out at suitable points to form the necessary chambers and burner openings and which, by reason of its particular construction, may be easily and quickly attached or removed from the respective bed plate.

Another object is to provide an efficient means for shielding the jet openings from the deteriorating effects of the heat and from becoming clogged by the ashes or other solid matter falling from the grate.

Another object is to provide for spreading the jets of fluid fuel after it emerges from the jet openings, so that the spreader cooperates with the row of jet openings and forms a sheet of fluid, thereby assuring the 5 igniting of all of the jets when one of them is ignited.

A further object of my invention is to provide a device of the type in question that is extremely simple in construction, strong and durable, and highly practical from both the standpoint of the manufacturer and the standpoint of the user; and which, it is believed, may be manufactured at a comparatively low cost.

Various other objects and advantages will become apparent during the continuance of the following description.

These objects are accomplished by such means as are shown in their preferred form in the accompanying drawings, described in the following specification and then more specifically pointed out in the appended claim.

In the accompanying drawings wherein

like characters designate like parts throughout the several views:—

Figure 1 is a view in plan of a grate and bed plate of substantially the conventional form showing my invention in conjunction therewith;

Fig. 2 is a view in longitudinal section of the burner showing more clearly the manner of attaching the same to the bed plate of the grate;

Fig. 3 is a cross sectional view taken on 65 line 3—3 of Fig. 2.

In the drawings, I have shown a bed plate 10 that is of substantially the conventional form and which is designed to support a grate 11 of the usual construction. At certain points the base plate 10 is provided with suitable securing ears 12 and 13 respectively (see Fig. 1), to which the burner may be attached in the manner hereinafter described.

In reducing my invention to practice, I first provide a base 14 that is preferably constructed of a cast metal and which carries a depending enlargement 15 (see Fig. 2) which constitutes to a great extent the 80 body portion of the burner. Although not limiting myself in any way to the specific manner by which the base 14 and the enlargement 15 may be connected, it is pointed out that these two elements may be cast in 85 one piece, if it is so desired.

The enlargement 15 is cored out longitudinally as at 16 (see Fig. 2) to form a suitable mixing and fuel dispensing chamber while it is further provided with lateral 90 burner jet openings 17 through which the fuel may find egress. These openings 17 may be arranged in any desired and well known manner so as to project the flame through the grate 11 into contact with the 95 fuel lying thereon; but, by means of a horizontal extension or spreader 17' I prefer to direct the flame from the jets 17 horizontally under the grate 11 and allow the draft of the stove to draw the flame through the 100 grate into the solid fuel. The spreader 17' also constitutes a shield for the jet openings, and also a reinforcement for the mixing chamber, to support the latter and to receive the brunt of the deteriorating effects 105 of the heat.

In connecting the burner to the said plate 10, the extended portion 14' of the base 14

of the burner is arranged to lie on the securing ear 13, as shown in Figs. 1 and 2 whereby a fastening member as designated at 18 may be passed therethrough, to attain 5 a secure connection while a second fastening member 19 may be passed through the other securing ear 12 into the enlargement 15, as shown in Fig. 2. By this arrangement, it will be noted that the burner may be 10 securely positioned in place and thus held against accidental dislodgment during the operation of the grate.

A nipple 20 may be connected with the enlargement 15 as at 21 to project exteriorly 15 of the stove and may be cut away as at 22 to provide a suitable air ingress opening. A nozzle 23 has its egress opening in the air inlet 22. A sliding cover sleeve 24 is arranged to be movable on the nipple 20 20 whereby it may be utilized to regulate the admittance of air through the cut away portion 22, or to completely close the same in the event that such is required by the operator. A usual gas pipe 24' may be connected 25 with the nipple 20 in the ordinary manner and egress thereinto controlled through the instrumentality of a suitable valve such as designated by the numeral 25.

In the operation of the burner, the sleeve 30 24 is first arranged on the nipple in a desired manner so as to regulate the ingress of air through the cut away portion 22 after which the gas may be turned on by way of the valve 25, and the mixture of air and 35 gas takes place in the mixing chamber 16 and may be lighted upon egress through the openings 17. As before stated the ingress of air through the cut away portion 22 may be adequately regulated so that the 40 proper mixture of air and gas may be attained.

From the foregoing it is apparent that I have provided an improved burner that may be quickly and easily attached to or removed 45 from conventional forms of bed plates and

cast in a single piece, whereby it may be manufactured at a minimum cost. In view of the fact that the advantages and novel features of my invention will be readily apparent from the foregoing, it is believed 50 that further detail description is deemed unnecessary.

In reducing my invention to practice, I find that the form referred to herein as the most practical and preferred embodiment 55 is the most efficient, but realizing that certain conditions will necessarily vary in concurrence with the adoption of my device, I desire to emphasize the fact that various minor changes in the details of construction 60 and in the proportion of parts may be resorted to when required without sacrificing any of the advantages of my invention as defined in the appended claim.

Having thus fully described my invention, 65 what I claim as new and desire to secure by Letters Patent is:—

In combination, a grate rest of substantially U-shape having inwardly extending ears at the extremities of the spaced members, and a fuel burner bridging the space between the said members and forming connecting means therefor, said burner comprising a lower hollow portion, which at one end underlies one of the said ears and 75 is attached thereto, and an upper plate portion which is extended at one end and overlies the remaining ear and is attached thereto, and which projects inwardly to overhang the said hollow portion, the latter having a plurality of openings in its inner wall adjacent the overhanging portion of the plate.

In testimony whereof I affix my signature in presence of two witnesses.

JOHN O. BURMAN.
